(57) **CLAIM**

The ornamental design for an actuator knob for a rod and tube assembly, as shown and described.

DESCRIPTION

FIG. 1 is a top isometric view of an actuator knob for rod and tube assembly;

FIG. 2 is a bottom isometric view thereof;

FIG. 3 is a top view thereof;

FIG. 4 is a bottom view thereof;

FIG. 5 is a front view thereof;

FIG. 6 is a rear view thereof;

FIG. 7 is a right side view thereof;

FIG. 8 is a left side view thereof; and,

FIG. 9 is a right side view thereof shown in an alternate position.

The broken line showing of the knob is for the purpose of illustrating portions of the knob and forms no part of the claimed design.

1 Claim, 7 Drawing Sheets
